(57) **CLAIM**

We claim the ornamental design for a side view mirror electro optic device with blind spot indicator portion, as shown and described.

DESCRIPTION

FIG. 1 is a front top perspective view of a side view mirror electro optic device with blind spot indicator portion of the present disclosure;

FIG. 2 is a rear top perspective view thereof;

FIG. 3 is a front elevational view thereof 1; and,

FIG. 4 is a rear elevational view thereof.

The broken lines illustrate portions of the article that form no part of the claimed design. The dash dot dash broken lines depict the boundary of the claimed design and form no part thereof.

The diagonal shading with intermittent breaks in FIGS. 1 and 3 represents a highly reflective surface, while the remaining diagonal shading on the front and rear surfaces of the article illustrates a transparent appearance.

The thickness of the element between the front and rear surfaces of the article forms no part of the claim.

1 Claim, 4 Drawing Sheets
